UNITED STATES PATENT OFFICE.

GEORGE LEHMANN, OF FOREST PARK, ILLINOIS.

DIMMER FOR AUTOMOBILE HEADLIGHTS.

Application filed November 3, 1921. Serial No. 512,583.

To all whom it may concern:

Be it known that I, GEORGE LEHMANN, a citizen of the United States, residing at Forest Park, in the county of Cook and 5 State of Illinois, have invented certain new and useful Improvements in Dimmers for Automobile-Headlights; and I do declare the following to be a full, clear, and exact description of the invention, such as will enable others skilled in the art to which it 10 pertains, to make and use the same.

This invention relates to an improved attachment for automobile headlights which serves to dim the light and to eliminate the 15 undesirable glare which is so troublesome and dangerous to drivers of approaching machines.

The principal object of the invention is to 20 provide a simple and inexpensive attachment which is capable of being applied on the exterior of the headlight, this attachment being held in place by tying means, thus permitting it to be easily and readily applied or removed whenever necessary or 25 desired.

More specifically speaking, it is another 30 object of the invention to provide a dimmer which is in the form of a strip of semi-transparent fabric which is placed over the exterior of the lens at the center of the same so as to eliminate the undesirable glare at 35 this point, this fabric having an elastic retaining element associated therewith for holding it in position on the light and the fabric being so constructed as to permit it to be effectively applied on all sizes of head- lights.

Other objects and advantages of the invention will be apparent during the course 40 of the following description.

In the accompanying drawings forming a part of this specification and in which like numerals are employed to designate like parts throughout the same:

45 Figure 1 is a side elevational view of a conventional form of headlight with my improved dimmer attached thereto showing clearly the manner of adjusting the same to fit the light.

50 Figure 2 is a front elevational view of the headlight showing the position of the attachment more clearly.

Figure 3 is a detail perspective view of the attachment removed from the light.

55 Figure 4 is a detail section taken sub-

stantially on the plane of the line 4—4 of Fig. 1.

As previously suggested, the improved dimmer is in the form of a semi-transparent elongated strip of comparatively heavy or 60 thick fabric 1 which is adapted to be disposed horizontally across the exterior of the central portion of a headlight lens L, this strip being of a length to permit its ends to be extended over the lens holding rim R and 65 beyond same so that they terminate adjacent the forward end of the body B. When placing the attachment on the light, it is arranged directly in front of the bulb so as to affect the extremely undesirable rays 70 which issue from this point and to modify and dull the light to a considerable degree. By carefully examining the dimmer it will be seen that the edges of the fabric are folded over and stitched as indicated at the 75 point 2 and one end is doubled upon itself and stitched to form what may be conveniently termed a pocket 3. At its opposite end, the fabric is formed with a plurality of rows of alined openings 4 which serve a 80 purpose to be hereinafter described and the edges of these openings are reinforced by small brass rings 5 or the like which are attached to the fabric in any suitable way. These rows of holes constitute a means 85 whereby the attachment can be effectively applied on different sizes of headlights. For the purpose of holding the fabric in position on the light, I make use of a yieldable retaining element 6 which is preferably composed of some elastic material. This retaining element is held in the aforesaid pocket 3. 90

In use, the strip of fabric 1 is stretched across the central portion of the headlight lens as shown in the drawings and the ends 95 thereof are drawn over the retaining rim R. Then, the elastic retaining element 6, which has previously been placed in the pocket 3, is passed around the body of the light as indicated in the drawings and one 100 end thereof laced through the proper row of holes 4 and the free ends tied together. On some headlights, the outermost row of holes will be used and on others the innermost row would probably be selected. If the last 105 named row of holes should be selected, there would be a portion of the fabric left free to wave about. It is desired to eliminate this. Therefore, this surplus portion of material is folded upon itself and the outermost row 110

of openings is alined with the innermost row so that the retaining element can be laced through both rows to hold the surplus material in this folded state. The manner 5 of accomplishing this is indicated in the drawings. The manner suggested of taking care of this surplus material need not of course be followed, because in some instances, this surplus material could be entirely cut 10 off after the attachment is once adjusted to properly fit a particular headlight. It is also unnecessary to untie the ends of the elastic retaining element 6 because this can be simply slipped over the retaining rim in 15 removing and applying the attachment.

I claim:

A dimmer for automobile headlights comprising an elongated relatively narrow strip

of semi-transparent fabric material adapted for horizontal disposition across the central 20 exterior of the headlight lens, the opposite ends of said strip being intended to be drawn over and beyond the usual clamping rim, one of the ends of said strip of fabric being formed with a plurality of spaced vertical 25 rows of holes, the holes in each row being alined with one another, and a flexible retaining element connected to one end of said strip, said element being intended to be laced through a selected row of holes and 30 tied to hold the dimmer in operative position on the light.

In testimony whereof I have hereunto set my hand.

GEORGE LEHMANN.
